CLAIM

The ornamental design for a cover or the like, substantially as shown and described.

DESCRIPTION

FIG. 1 is a top front perspective view of a cover or the like, showing my new design;

FIG. 2 is a top plan view thereof;

FIG. 3 is a front elevational view thereof, the rear view being a mirror image thereof;

FIG. 4 is a right side elevational view thereof, the left side being a mirror image thereof;

FIG. 5 is a bottom plan view thereof;

FIG. 6 is a top front perspective view of a second embodiment of that shown in FIG. 1;

FIG. 7 is a top plan view thereof;

FIG. 8 is a front elevational view thereof, the rear view being a mirror image thereof;

FIG. 9 is a right side elevational view thereof, the left side being a mirror image thereof; and

FIG. 10 is a bottom plan view thereof.
